(57) **CLAIM**

The ornamental design for a remote controller with graphical user interface, as shown and described.

DESCRIPTION

FIG. 1 is a front, top and right side perspective view of a first image of a remote controller with graphical user interface, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is an enlarged screen image thereof;

FIG. 9 is an enlarged screen image of a second image thereof;

FIG. 10 is an enlarged screen image of a third image thereof;

FIG. 11 is a reference enlarged screen image showing the invention in use;

FIG. 12 is a front, top and right side perspective view of a first image of a remote controller with graphical user interface, showing a second embodiment of my new design;

FIG. 13 is a front elevational view thereof;

FIG. 14 is a rear elevational view thereof;

FIG. 15 is a left side elevational view thereof;

FIG. 16 is a right side elevational view thereof;

FIG. 17 is a top plan view thereof;

FIG. 18 is a bottom plan view thereof;

FIG. 19 is an enlarged screen image thereof;

FIG. 20 is an enlarged screen image of second image thereof;

and,

FIG. 21 is a reference enlarged screen image showing the invention in use.

FIGS. 8-10 and 19-20 are displayed in a transitional sequence. The process or period in which an image transitions to another forms no part of the claimed design.

The broken lines showing the remote controller and portions of the graphical user interface in the drawings form no part of the claimed design.
